UNITED STATES PATENT OFFICE.

HARRY L. GRANT, OF TAMAQUA, PENNSYLVANIA, ASSIGNOR TO ATLAS POWDER COMPANY, OF WILMINGTON, DELAWARE, A CORPORATION OF DELAWARE.

PROTECTING DEVICE FOR ELECTRIC DETONATORS.

Application filed November 20, 1925. Serial No. 70,387.

This invention relates to a protecting device for electric detonators of the character of that shown in my copending application, Serial No. 748,214, filed on November 6, 1924. 5 Like the device of the application referred to the protecting device of the present invention is intended to be applied to the lead-in wires of electric detonators and to serve, while in position, to establish a short circuit 10 between the two lead-in wires, so that any stray currents imposed upon the lead-in wires, outwardly of the point of application of said device, may not find their way to the detonator and prematurely explode the same. 15 and so that no difference in potential can be created between the lead wires inwardly of the point of application of the device, under the influence of accidental or stray currents imposed upon said wires.

20 I am aware of the fact that it has been proposed to short circuit the main firing cable leading from the blasting machine. However, that method is of utility only at the time of use. An important object of the 25 present invention is to provide a structure which will be operative with respect to the individual detonators, at all times between the time of manufacture of the detonator and until the same is actually exploded on 30 the job, the structure being of particular utility during the time that the detonator is being transported and while it is being handled about the work preliminary to the actual connection of its lead wires to the main 35 firing cable.

The present application is directed to the protection of a specific form of short circuiting shunt and method of applying the same to the lead-in wires of the individual blasting caps, with its inner end abutting and resting firmly against the terminal end of the usual insulation of the detonators. In the provision of a structure of this character, which is used only once and then thrown 45 away, it is of importance that it be of a simple and inexpensive nature and one adapted to be applied rapidly by automatic machinery. With this end in view, I have devised the shunt shown in the accompanying 50 drawing wherein:

Fig. 1 is a perspective view of one form of shunt prior to its compression upon the lead wires of the detonator.

Fig. 2 is a side view of a detonator having 55 the shunt of Fig. 1 applied thereto.

Fig. 3 is a perspective view of a modified form of shunt prior to its application to the lead wires, and

Fig. 4 is a side view of the detonator of Fig. 3 after application to the lead wires. 60

Like numerals designate corresponding parts in all of the figures of the drawing.

Referring to the drawing, 5 designates the conventional electric detonator and 6 and 7 65 designate the usual lead-in wires of said detonator.

In the ordinary use of the detonator the flow of current of sufficient strength past an igniting element 8, which connects the inner ends of the wires 6 and 7, explodes the 70 detonator. The lead-in wires are insulated, as indicated at 9 and 10, for some distance from the detonator and the ends of the lead-in wires are left bare beyond the point where the insulation terminates, to adapt them for 75 ready application to the firing cable, leading from a blasting machine.

In the form of the invention illustrated in Fig. 1 a small strip of metal, which may be aluminum, copper, lead or any other suitable conductive material, is bent to form a body 11 and ends 11^a 11^b. The bared portions of the wires of the detonator are passed through this structure and the ends 11^a and 11^b are forced downwardly upon the body 80 11 in such manner as to be firmly crimped or clamped upon the bared portions of the wires, with the insulating material abutting one edge of the shunt. The shunt is so positioned upon the lead wires as to lie obliquely 85 with respect thereto said lead wires entering the shunt at one corner and passing therefrom at the diagonally opposed corner. An advantage of this arrangement is that the shunt presents two forwardly facing, 90 cutting or scraping edges, one at the forward corner, or at the point marked α in Fig. 2, and the other at the point marked β , where the forward edge of the end 11^b crosses the lead wires. Thus, when the shunt is removed 95 by stripping it longitudinally from the wires, these forwardly facing edges exert a cleaning and scraping action which cleans and brightens the lead wires and adapts them 100 for effective electrical union with the main firing cable of a blasting machine.

The structure as illustrated in Figs. 3 and 4 is substantially like that illustrated in Figs. 1 and 2, except that in the case of the structures of Figs. 3 and 4, the confronting edges 110

of the bent over ends 11^b and 11^c are disposed upon a line that is oblique with respect to the length of the shunt but is substantially at right angles to the lead wires. 5
5 This structure also possesses the advantage of presenting two forwardly facing scraping edges, which operate in the same manner as described with respect to the forms illustrated in Figs. 1 and 2. In both forms the 10 oblique disposition of the shunt gives maximum contacting surface for a given length of shunt. It is not to be understood that the device is of utility only when actually touching the termination of the insulation. It 15 will give a very appreciable measure of protection even when spaced somewhat from the insulation because the influences which might bring about such difference in potential between the lead wires as to explode the 20 detonator, are not those sought to be created by an intelligent human agency but only those which might accidentally occur. Stray currents of such low E. M. F. as to escape ordinary notice constitute a marked source 25 of danger and are rendered absolutely harmless by this invention.

It is to be understood that the invention is not limited to the precise construction set forth but that it includes within its purview 30 whatever changes fairly come within either the terms or the spirit of the appended claims.

Having described my invention, what I claim is:

35 1. The herein described method of applying a short circuiting shunt to the lead wires of an electric detonator, which consists of bending a strip of conductive material to form a connecting body and two overturned, 40 inwardly directed ends, passing the bared portions of the lead wires through said structure and compressing said structure to cause it to bind firmly upon said lead wires with the shunt disposed obliquely with re-

spect to said lead wires and with the lead 45 wires entering at one corner of the structure and passing from said structure at the diagonally opposed corner.

2. A shunt of the character described comprising a sheet metal element of conductive 50 material, bent to form a connecting body portion and overturned inwardly directed ends, the confronting edges of the overturned ends being obliquely disposed with respect to the length of the shunt. 55

3. The combination with an electric detonator and its lead wires wherein said lead wires are covered for a portion of their length with an insulating material and are bare for the remainder of their length, of a 60 shunt formed of conductive sheet metal and comprising a body portion and oppositely directed inturned ends, said shunt being clamped upon the bared portions of the wires and lying close to terminal ends of the insulation thereon, said shunt being obliquely disposed with respect to said wires, so that the wires enter the shunt at one corner thereof and leave at the diagonally opposed corner. 70

4. The combination with an electric detonator and its parallel bifilar lead wires wherein said lead wires are covered with insulating material for a portion of their length and are bare for the remainder of 75 their length, of a shunt comprising a body portion and a pair of overturned ends, said shunt being clamped upon said wires close to the termination of the insulation with the body portion disposed upon one side 80 thereof and the ends disposed upon the opposite side thereof, the bared portions of the lead wires projecting materially beyond said shunt to serve to attach the detonator to a common firing cable. 85

In testimony whereof he affixes his signature.

HARRY L. GRANT.
